DRYING APPARATUS

Laurence E. Olcott, Akron, Cleveland C. Soper, Kent, Karl W. Gasche, Stow, and William T. Runals, Akron, Ohio, assignors, by mesne assignments, to The Firestone Steel Products Company, Akron, Ohio, a corporation of Ohio

Application April 15, 1932, Serial No. 605,484

2 Claims. (Cl. 34—12)

This invention relates to drying methods and apparatus, and more especially it relates to procedure and apparatus for drying storage battery plates after the latter have been coated with litharge (PbO) or red lead (Pb_3O_4) in the manufacture thereof.

The chief objects of the invention are to produce improved storage battery plates; to produce storage battery plates having an uncracked or uncrazed surface coating; to effect economy in the manufacture of battery plates; and to reduce the time required for drying the coated plates. Other objects will be manifest.

Of the accompanying drawings:

15 Figure 1 is a front elevation of apparatus embodying and adapted to carry out the invention, in its preferred form;

Figure 2 is a section on the line 2—2 of Figure 1;

20 Figure 3 is a section on the line 3—3 of Figure 1;

Figure 4 is a section on the line 4—4 of Figure 1;

25 Figure 5 is a side elevation of the apparatus as viewed from the left of Figure 1, parts being broken away for clearness of illustrating;

Figure 6 is a section on the line 6—6 of Figure 1, and

30 Figure 7 is a section on the line 7—7 of Figure 6.

In the drying of storage battery plates by our improved method, the wet plates, of which the positive plates are coated with a plastic mass of red oxide of lead and the negative plates are 35 coated with a similar mass of litharge, are passed successively and progressively through three regions or zones of different conditions of temperature and humidity, namely, a preheating zone, a humidity zone, and a drying zone.

40 The passage of the work through the pre-heating zone requires approximately 12 per cent of the time required for complete drying. In this zone the temperature varies from room temperature to 180° F. maximum, or whatever temperature 45 is being maintained in the humidity zone. It is likely that there is increasing humidity in the pre-heating zone toward the region thereof of highest temperature. In this zone the work is gradually warmed without causing any drying 50 of the coating on the plates.

Passage of the work through the humidity zone requires about 44 per cent of the total time. The temperature in this zone may be as high as 180° dry bulb with the wet bulb 4 degrees lower. 55 Preferably the temperature used with positive

plates is about 5 degrees higher than that used with negative plates. The humidity in the zone is practically 100 per cent, that is, there is complete saturation of the atmosphere. In this zone the humid atmosphere keeps the outside of the 5 work in wet condition, so that the drying thereof is initiated from the interior of the viscous coating.

The passage of the work through the drying zone requires about 44 per cent of the total time. 10 The temperature in this zone is maintained between 250 and 280 degrees, although a temperature of 300 degrees may be used if desired. The heat in this zone is dry heat, and the temperature employed depends upon conditions of drying. 15 The major part of the drying of the work occurs in the drying zone, the drying progressing from the interior to the surface of the coating on the plates.

Both the humidity zone and the drying zone 20 are gas fired, and the products of combustion go directly into the air which circulates within said zones. Sufficient amount of gas is burned, and cooled if necessary, so that the air going into these zones has a CO_2 content of from 2 to 4 per 25 cent determined by the Orsat method. The function of the CO_2 in the drying atmosphere is to combine with the litharge or red lead on the battery plates to form a hard protective surface layer of lead carbonate ($PbCO_3$) thereon. This layer 30 is hard and coherent, and because the coating is dried from the interior outwardly, is uncracked or uncrazed. Thus it prevents flaking off of the coating during subsequent service use.

35 Referring now to the drawings wherein is illustrated the apparatus employed for the practice of the foregoing method, there is provided a relatively large closed oven 10 at one end of which is a somewhat narrower downward extension 11. Interiorly of the extension 11 is a transverse vertical partition 12 that divides the extension substantially in half, and extends well up into the oven. Within the oven 10 is an enclosed chamber of which the aforesaid partition 12 is one end wall thereof, horizontal partition 13 is the 40 top, vertical partition 14 is the other end wall, and partitions 10a, 10b are the front and rear side walls thereof, said side walls being spaced from the side walls of the oven as is most clearly shown in Figures 5 and 6. Within said chamber 45 are partitions 15, 16 that extend from the bottom thereof to points adjacent but spaced from the chamber-top 13.

That portion of the oven that is between partitions 12, 15 is the pre-heating zone and is desig- 55

nated A. The interior of the enclosed chamber between partitions 15, 16 is the humidity zone and is designated B. That portion of the oven above partition 13 is the drying zone and is 5 designated C. There is a somewhat indeterminate region between zones B and C between partition 16 and the adjacent end wall of the oven.

The space between partition 12 and the adjacent end wall of the oven is not heated, and in 10 here the work cools somewhat before it is delivered from the oven.

Extending through the several zones of the oven is an endless conveyor 18 comprising parallel sprocket chains 19, 20 (Figures 5 and 6) that 15 carry between them a multiplicity of pivotally suspended supports or trays 21, 21. Work supported upon said trays is designated 22. The chains 19, 20 are trained about a series of suitably mounted sprockets 23, 23, and a pair of sprockets 20 24 that are mounted upon a shaft 25 that extends through the wall of the oven and is provided exteriorly of the latter with a sprocket 26 that is driven by a chain 27 from a suitable source of power (not shown). The conveyor is driven in 25 the direction indicated by the arrow in Figure 7, and is disposed in loops within the oven zones B and C so that the work remains in these zones for the required interval of time.

In the lower part of the oven extension 11 is a 30 work-receiving orifice 30 opening into the pre-heating zone A, and positioned adjacent said orifice, exteriorly of the oven, is a gravity conveyor 31 for the work, said conveyor preferably being provided with suitable release mechanism 35 32 that is successively actuated by trays 21 whereby automatic loading of the latter is effected.

In the opposite side of the oven extension 11 is a work-delivery orifice 33 opening into the unheated, cooling zone of the oven, and a gravity 40 conveyor 34 extends through said orifice and into the path of conveyor 18 in such a manner as automatically to remove the work from the trays 21 of the conveyor, and to deliver the work to the place desired.

45 At the bottom of the oven extension 11 is a well 36 in which is a cooling fluid 37 such as water. An inlet pipe 38 and an outlet pipe 39 are provided for said well, the outlet pipe serving to keep the fluid at a determined level. The arrangement 50 is such that empty trays 21 of the conveyor 18 pass through the cooling fluid 37 just before they receive work from the gravity conveyor 31, so that the cooled trays transmit no heat to the work.

The pre-heat zone A is arranged to draw some 55 air from the top of the humidity zone B over the top of partition 15. Also there is provided a motor driven fan 40 that has an intake duct 41 extending interiorly of the oven to an opening 42 into the humidity zone B, said duct having a branch 43 60 (Figures 5 and 6) extending across the end of the oven and opening into the lower part of the cooling zone, between the partition 12 and the end of the oven. The fan 40 has a delivery duct 44 disposed between the oven wall and wall 10a, and 65 opening into the pre-heat zone at one or more points 45, 45 depending upon the desired control, which may be regulated from the outside. Fresh air enters the pre-heat zone through orifice 30. The arrangement is such that the atmosphere in 70 the pre-heat zone is progressively warmer and more humid as it approaches the entrance to the humidity zone.

Mounted upon the front side of the oven 10 75 exteriorly thereof is a humidifier 48 at one end of which is a motor driven fan 49 having an exhaust

duct 50 that is disposed between the walls 10 and 10a and has a discharge orifice 51 in the lower part of the humidity zone B. The humidifier has an inlet duct 52 having two inlet ports 53, 54 respectively opening into the humidifier and into the passage between the humidity zone B and 5 drying zone C. The humidifier 48 recirculates the air within the humidity zone.

It is of standard construction and includes steam coils (not shown) for heating the air passing therethrough, and a steam jet (not shown) for humidifying the air. Near the point where the inlet duct 52 enters the humidifier is a gas burner 55 that is so arranged that the products of combustion containing CO₂ go into the recirculating 15 air stream.

Also mounted upon the outside wall of the oven, beside the humidifier, is a heating unit 58 of the usual type including heating coils (not shown). At one end the heating unit 58 is connected to an inlet duct 59 (Figure 6) that has an inlet port in the wall of oven 10 and takes in air from between the walls 10, 10a. At the opposite end of the heater 58 is a motor driven fan 60 that has a fresh air intake 61, and an exhaust duct 62 25 that extends through the adjacent oven wall and across the top of humidity zone B. The duct 62 has branch ducts 63, 63 extending laterally between the walls 10, 10a and 10, 10b, each of said branch ducts being provided with a plurality of 30 outlet ports 64, 64. Connected to the heating unit 58 is a gas burner 65 similar to that shown at 55. The heating unit 58 supplies heat and gas to the drying zone C.

The drying zone C has a vent 67 to the exterior 35 of the oven, said vent having a damper therein. A similar vent 68 is provided for humidity zone B. Below the oven 10 is mounted a motor driven suction fan 69 having an inlet duct 70 (Figure 5) communicating with the lower region of the pre-heating zone A, said fan having a discharge duct 71 extending to the roof of the building that houses the oven. The vents 67, 68 and exhaust duct 71 are used for purging the oven of all gas before starting operation. They may also be 40 used to control the amount of moisture recirculated in the system.

The air in the respective zones of the oven is 45 kept constantly in circulation, so that uniformity of temperature, humidity, and gas content is 50 maintained. The method and apparatus conserve time in the manufacture of storage battery plates, improve working conditions, and achieve the other objects set out in the foregoing statement of objects.

Modification may be resorted to without departing from the spirit of the invention, or the scope of the appended claims which are not limited wholly to the specific construction shown or exact procedure described.

What is claimed is:

1. In drying apparatus the combination of an oven comprising a pre-heating compartment, a humidifying compartment and a drying compartment, an endless conveyor traversing said compartments, a humidifier, means for recirculating air through the humidifier and through the humidifying compartment, a heater, means for recirculating dry air through the heater and through the drying compartment, and respective 70 gas burners so connected to the humidifier and to the heater as to inject the products of combustion of said gas burners into the air streams passing through said humidifier and heater.
2. Apparatus for drying storage battery plates 75

containing a thick viscous paste, said apparatus comprising an endless conveyor and a series of compartments traversed by said conveyor, the latter being adapted to carry battery plates placed 5 thereon successively through said compartments, said compartments comprising a preheating compartment, means for heating the atmosphere in said compartment for heating said plates and the paste thereon, a humid atmosphere compartment, 10 means for humidifying the atmosphere in said compartment for preventing the surface of said paste from drying before the interior thereof, a drying compartment, means for removing humidity from the atmosphere in said drying compartment for removing the moisture from said 15 paste, means for continuously driving said conveyor for progressively presenting said plates to said pre-heating compartment, said humidifying compartment, and said drying compartment,

means for directing the conveyor through a path in the preheating compartment for a distance approximately 12% of the total distance of travel of said battery plates in said apparatus, in the humidifying compartment approximately 44% of 5 the total distance of travel of said battery plates and in the drying compartment approximately 44% of the total distance of travel of said battery plates, whereby plates carried by the conveyor will be treated in the respective compartments for periods correspondingly proportional to the total time of treatment, as the conveyor moves through the compartments at a substantially uniform speed.
